POCKETBOOK TOP

Application filed October 25, 1929. Serial No. 402,402.

Our present invention relates generally to a handbag and a frame therefor and more particularly to the employment of locking means with a frame of the inverted channelled type.

In our Patent 1,729,599, granted to us on September 24, 1929, we show a handbag employing an inverted frame in which the lock operating means are so associated with the upstanding walls of the frame as to derive some or all of their yieldability from their manner of association with these upstanding walls.

One of the objects of the present invention is having this association of such a character as will prevent the walls which define each channel from separating or spreading apart.

One of the important features of our invention resides in the simplicity of the frame construction and the advantages it presents both from the standpoint of the association of the bag fabric therewith and of the character of the resulting bag when completed.

For the attainment of the foregoing objects and such other objects as may herein-after appear or be pointed out, we have illustrated one embodiment of our invention in the accompanying drawings wherein—

Figure 1 is a front elevational view of our frame;

Figure 2 is a side elevational view thereof in closed position, the dotted lines showing the frame structure in open position;

Figure 3 is an enlarged cross-sectional view taken on lines 3—3 of Figure 1 with the handbag fabric shown in dotted lines;

Figure 4 is a top plan elevation looking down upon the frame of Figure 1;

Figure 5 is a perspective view of the bag employing the frame of Figure 1.

Upon viewing the drawing of Figure 1, it will be observed that our invention is illustrated as embodied in a frame structure adapted to provide a handbag having an inner compartment and an outer compartment, although it will be understood that the present invention is directed specifically to the frame for the outer compartment and the handbag employing it.

The reference character 10, is applied in

Figure 1, to the main or outer frame and reference character 11, to the inner frame. The frame 10, as shown more clearly in Figures 2, 3 and 4, comprises the two U-shaped members 15 and 16, each pivoted at the free ends of the legs of the U to the aligned pins 18. Each of the frame members 15 and 16 of the main frame is in the form of a metal stamping, and U-shaped in cross-section as shown more clearly in Figure 3 to provide inner and outer upstanding walls 20 and 21, and a bottom 22. The channel 23, formed in each frame between these walls and bottom, it will be observed, extend upwardly and outwardly for purposes that will be hereinafter more fully pointed out.

Secured to the outer wall 21, of the channel 23, in each of these frame members 15 and 16 and preferably at a point substantially midway of the connecting web or bottom 22 of the U is an upstanding lock operating member 24 or 25. These members operate the interengaging locking portions 26 and 27 which in the illustrative embodiment are associated therewith, (see Figure 4) and serve as the means for holding the two frame members 15 and 16, in closed position. The application of pressure to the members 24 and 25 in opposite directions will cause the locking members 26 and 27 to spring past each other either in opening or closing the frame 10.

The inner frame structure 11, is formed of two frame members, also each generally in the form of a U and also each pivoted at the free ends of the legs of the U on the aligned pins 18, which pins are made sufficiently long to serve as bearings for the legs of both frames.

The lock operating members 24 and 25, are each illustrated in the drawings as in the form of open frames, the advantage of which will be well understood.

In the manufacture of the bag, the bag material (see 30 of Figure 5) is caused at its upper end to engage about the outer surface and over the top of the outer walls 21 of the channels 23, of the outer frame member and the free upper edges thereof forced or passed into the channels 23 and secured

therein in any desired or preferred manner. To permit this it may be advisable in the illustrated embodiment, to slit the upper edges of the fabric so as to permit it to be 5 passed around the supporting legs 31 and 32 of the lock operating members 24 and 25.

One of the important features of my invention is that because of the manner in which the lock operating members 24 and 25 are 10 supported each from one of the walls of the frame, each lock operating member is in fact a yielding support so as to permit of a spring operation of the locking members 26 and 27. As a result of this, the members 24 and 25 15 can be constructed both as to the character and thickness of material and as to contours without necessitating that the spring action be inherent in them.

The inner frame 11, is, as already set forth, 20 of the more or less conventional type and the fabric is secured thereto in any desired or preferred manner, to form the inner container of the handbag and as the manner of the construction of the inner pocket has no bearing upon our invention, no further description thereof is believed to be necessary.

In Figure 5, of the drawings, we have shown in perspective a finished handbag employing the frame structure of Figure 1 and 30 it will be understood from the description of the construction of the outer frame members 15 and 16, and of the manner in which the material of the outer bag is associated therewith, and of the relationship thereto of 35 the position of the lock operating members 24 and 25, and the desired results are attained.

Having thus described our invention and 40 illustrated its use, what we claim as new and desire to secure by Letters Patent is—

1. A handbag frame comprising U-shaped members hinged to each other at the free ends of the legs of the U, each member being in the form of a stamping channeled inwardly to provide opposed spaced inner and outer walls extending upwardly and outwardly and an upwardly and outwardly extending channel therebetween, whereby the upper and outer ends of the handbag fabric can be 45 passed over the outer surfaces of the outer walls of the channels and over the top edges of such walls and secured in position in such channel, locking members for holding said frame members against separation and operating members therefor, all operatively associated with the said outer walls, and presenting the channels substantially unobstructed whereby said outer walls add to the 55 resiliency of the lock operating members and the lock operating members when in locked association tend to prevent the spreading of the opposed walls of each channel.

2. A handbag frame comprising U-shaped members hinged to each other at the free 60 ends of the legs of the U, each member being

in the form of a stamping channeled inwardly to provide opposed spaced inner and outer walls extending upwardly and outwardly and an upwardly and outwardly extending channel therebetween, whereby the upper and outer ends of the handbag fabric can be 70 passed over the outer surfaces of the outer walls of the channels and over the top edges of such walls and secured in position in such channel, locking members for securing said frame members against separation and operating members therefor, all carried by the said outer walls, said operating members extending upwardly from and substantially in the plane of the outer walls, the locking members and the operating members therefor 75 presenting the channels substantially unobstructed whereby said outer walls add to the resiliency of the lock operating members when in locked association and the lock operating members tend to prevent the spreading of the opposed walls of each channel.

3. A handbag frame comprising U-shaped members hinged to each other at the free ends of the legs of the U, each member being in 80 the form of a stamping channeled inwardly to provide opposed spaced inner and outer walls extending upwardly and outwardly and an upwardly and outwardly extending channel therebetween, locking members for securing said frame members against separation and operating members therefor, all carried by the said outer walls, said operating members extending upwardly beyond the upper edges of the outer walls, and handbag 85 fabric passed over the upper edges of and about the outer walls and into the channels and presenting the channels substantially unobstructed whereby said outer walls add to the resiliency of the lock operating members and the lock operating members when in locked association tend to prevent the spreading of the opposite walls of each channel.

In witness whereof we have signed and sealed this specification.

CHARLES J. McCABE.
IRVING SCHOENHOLZ.
